(57) CLAIM

The ornamental design for a handle for kitchen tool, as shown and described.

DESCRIPTION

FIG. 1 is a top perspective view of the handle for kitchen tool showing my new design;

FIG. 2 is a top plan view thereof;

FIG. 3 is a bottom plan view thereof;

FIG. 4 is a side elevation view, the opposite side view is identical; and,

FIG. 5 is a right end view thereof.

The broken line showing of a tool head in FIGS. 1-5 is for illustrative purposes only and forms no part of the claimed design.
